UNITED STATES PATENT OFFICE.

GEORGES COUTIE, OF PARIS, FRANCE.

TOOTH FACING.

Application filed January 14, 1927, Serial No. 181,114, and in France March 5, 1926.

This invention relates to the construction of artificial teeth and dentures and has more particular reference to the type of partial or hollow artificial teeth made of porcelain known as tooth-facings adapted to be anchored to metallic dentures such as 5 bridges, caps and plates.

A primary object of the invention is the provision of an improved tooth-facing of 10 very light and thin structure comprising no gingival bevel or protuberance whereby its outer face can evenly merge with the face of the gum and thus absolutely give the appearance of a natural tooth.

15 A further object of the invention is the provision of a tooth-facing the anchorage of which on the metallic bridge, cap or plate is performed by improved dovetailed means whereby said tooth-facing is more securely 20 held in position.

A still further object of the invention is the provision of an armoured tooth-facing embodying a metallic lining wherein the anchorage dovetailed means are formed before 25 the porcelain facing proper is moulded thereon.

A still further object of the invention is the provision of improved means for shaping the metallic lining preparatory to the moulding of the porcelain body of the tooth-facing.

With the above and such other objects in view as will incidentally appear hereafter, the invention consists of the novel devices 35 and combinations of devices and methods that will now be described with reference to the drawing and defined in the claims.

In the accompanying drawing:—

40 Figure 1 is an elevational view on a very large scale of an incisor tooth-facing according to the invention, viewed internally so as to disclose its anchoring dovetailed groove.

45 Figure 2 is a longitudinal sectional view thereof.

Figure 3 is a front elevational view on a smaller scale of a metallic molar support showing its anchoring dovetailed key.

Figure 4 is an edge view thereof.

50 Figure 5 is a plan view thereof more clearly showing the shape of the key.

Figures 6, 7 and 8 illustrate on a small scale and viewed from different positions the

die for manufacturing tooth-facings as shown in Figures 1 and 2. 55

As illustrated in Figures 1 and 2, the improved tooth-facing according to the invention is constituted by a cap-like or hood-like hollow member the outer front or visible wall 1 of which presents externally the size, shape and colour of a normal tooth whereby when in position upon a metallic bridge, cap or plate (not shown) it will have the appearance of such a tooth. The outer wall of this tooth-facing 1 is reduced in 60 thickness at its lower end as at 1^a i. e. cut according to such a sharp bevel shape as will permit it when in wearing position upon the metallic support to evenly merge with the face of the underlying gum (not shown) so as to avoid any protuberance or projection as in similar tooth-facings as proposed heretofore. 65

The wall 1 is elbowed at its crown end to 70 form a rearwardly extending bevelled extension 1^b for delineating a recess 2 which tapers and is undercut as at 3. The inner face of said wall 1 is formed with a longitudinal groove 4 undercut at 5 along each of its longitudinal edges for providing a dovetailed seat. This groove 4 is fairly wide at 75 its lower end i. e. at the mouth of the tooth-facing and it upwardly tapers in width whilst downwardly tapering in depth whereby it has a maximum width and a minimum depth adjacent said mouth. The progressive increase of depth of the groove 4 in the upward direction may substantially correspond to the increase in thickness of the tooth-facing in said direction. 80

The groove 4 thus presenting a dovetailed and tapering shape forms a seat wherein may be inserted a correspondingly shaped key or block 6 formed upon the metallic bridge, cap or plate (see Figures 3, 4 and 95 5) whereby an anchoring or wedging effect is secured as will be described hereinafter.

The grooves 4 in all the tooth-facings and the keys or blocks 6 on the denture parts may be standardized to reduce cost of production and also to permit a new tooth-facing to be readily fitted and fixed in position should one have been broken, all such tooth-facings being thus rendered interchangeable. 100

Such tooth-facings may be made of por-

celain or other suitable material and they may also, for the sake of resistance and as will be described hereafter, be internally reinforced or armoured, during manufacture, by fine wire netting or mesh or a plain or foraminous plate.

For manufacturing a tooth-facing as above described, a metal die 7 such as the one represented in Figures 6, 7 and 8 is used. Said die is supported by a base 8 of conventional shape and size and it is provided with a rounded or convex shape substantially corresponding to the one of the recess to be formed in the hollow tooth-facing. It is furthermore surmounted by a dovetailed rib or ridge 9 having a tapering outline as clearly shown in Figure 6 i. e. such an outline as to taper in width in the one direction whilst tapering in thickness in the other direction. Thanks to this shape of the die 7, a thin sheet of metal or gauze such as platinum or gold may be applied upon the tapering ridge 9 and stamped or pressed into a correspondingly tapering shape so far as its groove is concerned. Such a sheet of precious metal having a dovetailed groove gradually reduced in width in the one direction whilst being gradually reduced in thickness in the opposite direction is afterwards used as a support for the porcelain or like body of the tooth-facing 1 which may be moulded, cast and secured thereon by the customary processes as used in the dental art whereby a tooth-facing internally reinforced or armoured by a precious metal lining is obtained. In the case of a gold lining, it may after having had the porcelain body moulded thereon be chemically removed by rubbing same with aqua regia or removed in a different way, whereby a tooth-facing entirely made of porcelain is finally obtained.

A tooth-facing as represented in Figures 1 and 2 and manufactured as has just been described with reference to Figures 6, 7 and 8 is adapted to be used in conjunction with a metal denture, crown, cap, bridge, plate or other support i. e. applied externally on said support for concealing any metal part and giving the appearance of a natural tooth whilst ensuring the dental advantages of a metal crown or bridge. To that end, the metal support 10 presenting the general shape of an incisor, molar or other tooth (see Figures 3, 4 and 5 wherein is illustrated by way of example a small molar support) is formed or provided on its outer face with a dovetailed key 11 the tapering shape of which is adapted to fit the one of the corresponding groove or seat 4 formed in the tooth-facing 1. By this arrangement, an anchoring effect is obtained owing to the wedging engagement of the key 11 in the seat 4. If required, said anchoring effect may be supplemented by interposing a thin layer of

cement or like binding substance between the porcelain tooth-facing and its metal support.

Owing to the particular undercut shape of the recess 2 formed in the tooth-facing 1 and to the peculiar tapering shape of its dovetailed groove, it will be held very securely in position either in the longitudinal or in the transverse direction irrespective of the cutting, tearing, chewing or other strains undergone by the tooth and its support.

It will be understood that depending on the kind of teeth to be provided with tooth-facings, the size of the said facings and particularly of their rearwardly extending crown parts 1^b will vary. Similarly the size and shape of the die 7 will vary to suit the same requirement.

What I claim is:—

1. A porcelain tooth-facing comprising an outer front wall progressively reduced in thickness from its crown to its mouth for merging with the gingival face, a rearward crown extension of said wall, a hollow recess delineated by said front wall and rearward extension, and a dovetailed groove formed in the back face of said front wall and having a depth gradually decreasing as the thickness of said wall and a width decreasing in the opposite direction.

2. A porcelain tooth-facing comprising an outer front wall gradually decreasing in thickness from its crown end to its mouth end for evenly merging with the gingival face, a rearward crown bevelled extension integral with said wall, an undercut hollow recess delineated by said front wall and rearward extension, and a dovetailed groove formed heightwise in the back face of said front wall and having a depth gradually decreasing from crown to mouth and a width decreasing from mouth to crown, the narrower and deeper portion of said dovetailed groove coinciding with the undercut portion of the recess in the tooth-facing.

3. A tooth-facing comprising in combination, on the one hand, a porcelain front wall gradually decreasing in thickness from its crown end to its mouth end for merging with the face of the underlying gum, a rearward crown bevelled extension integral with said wall, an undercut recess delineated by said wall and extension, and a dovetailed groove formed heightwise in the back face of said wall and having a depth gradually decreasing from crown to mouth and a width decreasing from mouth to crown and, on the other hand, an armouring metal lining of equivalent grooved shape fixedly secured to the back face of the porcelain front wall.

4. The method of manufacturing a tooth-facing of the type set forth consisting to use a suitably shaped and sized die having a dovetailed or laterally undercut ridge flaring in width in the one direction whilst tapering in thickness in the same direction,

to stamp or press a sheet of precious metal or gauze on said die for forming a tapering dovetailed groove therein and to mould porcelain or a similar substance on said 5 metal sheet according to a progressively reduced sectional shape for providing a thin bevel adjacent the mouth of the tooth-facing.

5. The method of manufacturing a tooth-

facing according to claim 4 further consisting to chemically remove its inner metallic 10 armouring plate for example made of gold by dissolving same out by means of aqua regia.

In testimony whereof I affix my signature.

GEORGES COUTIF.
